UNITED STATES PATENT OFFICE.

WILLIAM SCRIMGEOUR, OF LANCASTER, PENNSYLVANIA, ASSIGNOR TO MIRCS FUEL-OIL EQUIPMENT COMPANY, INCORPORATED, OF NORFOLK, VIRGINIA, A CORPORATION OF VIRGINIA.

GAS-HEATED FORGING OR WELDING FURNACE.

1,206,036.

Specification of Letters Patent. Patented Nov. 28, 1916.

Application filed May 4, 1914. Serial No. 836,287.

To all whom it may concern:

Be it known that I, WILLIAM SCRIMGEOUR, a citizen of the United States, residing at Lancaster, in the county of Lancaster and State of Pennsylvania, have invented certain new and useful Improvements in Gas-Heated Forging or Welding Furnaces, of which the following is a specification.

10 My invention relates to a heating furnace, in which the metal blanks or other objects are heated by gas.

It further relates to the means for pre-heating the gas and air prior to their combustion, these means comprising an arrangement of flues through which pass the highly heated products of combustion, and suitable preheating devices.

20 My invention further relates to the construction of these preheating devices and to the construction of the burners themselves.

The invention will be understood from the accompanying description and drawings, in which—

25 Figure 1 is a vertical longitudinal section of the furnace, showing the system of flues and a preheater and the burner in heating chambers; Fig. 2 is a horizontal section 30 on the plane A—O—B of Fig. 1; Fig. 3 is a horizontal section on the plane A—O—A of Fig. 1; Fig. 4 is a vertical transverse section on the plane C—C of Fig. 1, showing the air and burner preheating chambers; Fig. 5 is a front view of the furnace structure showing the fronts of the air preheaters and burners, and the buckstaves or 35 braces in place; Fig. 6 is a view of a modification, showing the preheaters projecting 40 into the preheating chambers from the sides instead of the front of the furnace; Fig. 7 is a horizontal section of the burner body shown in Figs. 1 and 2; Fig. 8 is a vertical transverse section of the burner body on 45 the line E—E of Fig. 7, with the air and gas nozzles removed; Fig. 9 is a vertical transverse section of the burner body on the line F—F of Fig. 7; Fig. 10 is a front view of the preheater; Fig. 11 is a view in 50 elevation of the preheater; and Figs. 12 and 13 are vertical longitudinal and transverse sections of the preheater, showing the radiating plates and partition.

In Figs. 1, 2, 3, and 4, the furnace 1 is built of suitable refractory material 2, and 55 contains a work-chamber 3, covered with a roof 4 which inclines downward toward the back and tends to curve the flame through the furnace, and a charging entrance 5, which may be closed by a sliding 60 door or other suitable means. An opening 7, which may be closed by a loose brick 70, is shown in the roof of the furnace in Fig. 1; and another opening 8, shown closed by a loose brick or cover 9, in Figs. 2 and 3, 65 provides for cleaning slag, etc., from the bottom of the furnace. The furnace is built upon foundation 10, containing transverse channels 11, through which pass bolts 12, Fig. 1, to secure suitable braces or buckstaves, not shown; and also longitudinal channels 13, Fig. 4, in which are secured by bolts or other means, not shown, the braces or buckstaves 13', Fig. 5.

The furnace is preferably heated by producer gas supplied through pipe 14, pre-heater 15, valve 16, opening 17', to gas chamber 17, Fig. 7, of burner 18, from which it passes out through gas-nozzles 19, 20, 21, into the furnace. Air is supplied 80 through the pipe 22, Fig. 5, preheater 23, valve 24, to opening 25, air inlet 25 and air chamber 26 of burner 18, from which it passes out through air nozzles 27, burning gas in the combustion chambers 28, and 85 blowing the flames into the upper part of the work-chamber 3, through which they circulate and leave from the lower part through vents 52, 52'.

The burner 18, Fig. 7, consists of a distributing casing 18' divided by a partition 29 into gas chamber 17 and air chamber 26; the partition is pierced by threaded openings 30, 31, 32, into which are screwed the gas nozzles 19, 20, and 21; access to these 95 openings for adjustment and repair of the nozzles is had through the closed holes 33, 34, 35, and loose bricks 62, 63, 64, in the furnace wall, Fig. 2. On either side of the air inlet 25, Fig. 9, are passages 36, 36, through 100 which the gas passes to gas nozzle 21. On the air side of the burner casing, Fig. 7, are outlets 37, 38, 39, in which are secured the several air nozzles 27.

The preheaters 15 and 23 are alike in 105 structure, and are shown in detail in Figs. 10

to 13. A casing 40 is provided with inwardly projecting heat-radiating plates or ribs 41, and a flanged rim 42, to which latter is secured a cover 43, carrying a partition plate 44 which projects between the heat-radiating plates 41, thereby providing a return bend or channel within the casing. Openings 45, 46, in the cover 43 provide means for securing pipes 47, 48, respectively, 13 shown in Figs. 1 and 6, for conducting the air or gas.

The modification in Fig. 6 differs from that in Fig. 1 only in the insertion of the preheaters 49, 50, through the sides of the furnace, instead of through the front, as shown in Figs. 1, 3, and 5; and in supplying the air and gas through suitable openings in the ends of the burner casing 51, instead of along one side, as shown in Figs. 1 and 2.

20 The operation of the furnace is as follows:—The flames from the burner 18 and combustion chambers 28, Fig. 2, enter the work chamber 3, from which the heated gases may pass, in greater or less quantity, through opening 7 in the roof 4, this opening being partly or completely closed by a loose brick or damper 70. The heated gases also pass through an interconnected flue-system in the front wall of the furnace, comprising outlets 52, 52, Figs. 1 and 3, and a common or "omnibus" vent 52', Fig. 3, into the preheating chambers 53, 54, (Figs. 1, 3, and 4) passages 55, 56, burner heating chamber 57, and out the vents 58, 59, 60, 61, which 25 may be closed, partly or entirely, by a loose brick, one being shown at 71 in dotted lines over vent 61 in Figs. 1 and 4. The regulation of the openings 7, 58, 59, 60, 61 controls the quantity and direction of the heated 30 gases passing through the preheating chambers 53, 54, and burner chamber 57, thereby controlling the draft through the furnace and controlling the temperature of the incoming gases, and also obtaining a maximum 35 temperature within the work chamber for a given consumption of gas. The heated gases in passing through the preheating chambers heat the preheater casings 40, through which heat is conducted to the radiator plates or ribs 41, the latter, presenting an extended surface, uniformly heat the flowing gases to a high temperature. The products of combustion circulating around the burner 18 also raise its temperature, 40 thereby conserving the heat which the air and gas have absorbed while passing through the preheater, and also raise the temperature of the furnace walls, thereby preventing loss of heat from the combustion 45 chambers 28. On closing vents 7, 58, 59, the heated gases travel almost entirely through preheating chamber 53 and the corresponding end of the burner chamber 57, and out through vents 60 and 61; conversely, on opening vents 58 and 59, and

55 closing vents 60 and 61, the preheating chamber 54 and corresponding end of burner chamber 57 will receive the most heat.

I claim:—

1. In a furnace, a refractory structure, a work-chamber therein, gas burners to heat said work-chamber, an interconnecting flue-system leading from said work-chamber to conduct heated gases from said work-chamber, comprising preheating chambers, gas and air heaters in said chambers, a separate vent from the work-chamber to each preheating chamber, an omnibus vent to the preheating chambers, a burner-heating chamber, separate vents from each preheating chamber to the burner-heating chamber, and a plurality of controllable outlets from the burner chamber. 70

2. In a furnace, a refractory structure, a work-chamber therein, a combustion chamber opening into the upper part of the work-chamber, outlets from the lower part of the work-chamber, preheating chambers, a burner-heating chamber, a system of vents arranged to conduct predetermined quantities of the products of combustion to the preheating chambers, flues connecting the preheating and burner chambers and controlled outlets to conduct the products of combustion in a predetermined direction 80 through the preheating and burner chambers. 90

3. In a furnace, a refractory structure, a work-chamber therein having a roof slanting toward the wall opposite the combustion chambers, a closable outlet in the roof of said furnace, combustion chambers opening into the upper part of said furnace, outlet vents from the lower part of said furnace, preheater chambers and a burner-heating chamber, a system of interconnected flues to conduct heated gases first into the preheater chambers, then into the burner-heating chamber, and closable outlets from said burner-heating chamber. 100

4. In a furnace, a refractory structure, a work-chamber therein, a gas burner to heat said work-chamber, an interconnecting flue-system in the refractory structure, a plurality of chambers in proximity to each other and constituting a part of said flue-system, two of said chambers constituting preheating chambers and arranged to receive heated gases in parallel from said work-chamber, a gas preheater in one of said preheating chambers, an air preheater in the other of said preheating chambers, outlets from said preheating chamber leading into a burner-heating chamber, and pipe connections and valves connecting said gas preheater and air preheater with said gas burner. 115

5. In a furnace, a refractory structure, a work-chamber, gas burners to heat said work-chamber, a system of flues leading 120

from said work-chamber, preheating chambers in said refractory structure and connected to said flues, a gas preheater, an air preheater, said gas and air preheaters in preheating chambers and arranged to be heated by the products of combustion from said combustion chamber, and means to create a greater draft over one preheater than the other, thereby conducting a greater

quantity of products of combustion over one 10 preheater than over the other.

In testimony whereof I affix my signature in presence of two witnesses.

WILLIAM SCRIMGEOUR.
